CLAIM

The ornamental design for a collapsible foot spa massager as shown and described.

DESCRIPTION

FIG. 1 is a perspective view of a collapsible foot spa massager, showing my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof.

FIG. 8 is an exploded perspective view of the collapsible foot spa massager.

FIG. 9 is another exploded perspective view of the collapsible foot spa massager; and,

FIG. 10 is a perspective view of the collapsible foot spa massager shown in a folded state.

The broken lines in the drawings and the portions shown in a de-emphasized faded out and halftone form represent portions of the collapsible foot spa massager that form no part of the claimed design.
